SAMUEL B. WAIT, OF MARINER'S HARBOR, NEW YORK.

Letters Patent No. 62,238, dated February 19, 1867.

IMPROVED PROPELLER.

The Schedule referred to in these Letters Patent and making part of the same.

TO ALL WHOM IT MAY CONCERN:

Be it known that I, SAMUEL B. WAIT, of Mariner's Harbor, (Staten Island,) in the county of Richmond, and State of New York, have invented a new and useful improvement in Propelling Vessels; and I do hereby declare that the following is a full, clear, and exact description thereof, which will enable others skilled in the art to make and use the same, reference being had to the accompanying drawings, forming part of this specification, in which—

Figure 1 is a side elevation partly in section of a vessel which is provided with my improved apparatus.

Figure 2 is part of a top view of the same.

Figure 3 is a rear elevation of the same.

Similar letters of reference indicate like parts.

The object of this invention is to provide a new manner of propelling vessels, employing the oar principle at the stern of a ship, said oars being moved in such a manner by machinery that the full power of each stroke is utilized. The invention consists in securing to an oscillating upright shaft, which is secured at the stern of a vessel in front of the rudder, a horizontal sleeve, wherein a horizontal shaft is held. From a machine inside of the vessel, an oscillating motion is imparted to this horizontal shaft, and thus the same receives a double oscillating motion, once around its own axis, and then around the axis of the vertical shaft. To the horizontal shaft, near its ends, are secured metal or other plates, which act as oars or paddles, and which, by reason of the motion of the horizontal shaft, are turned up and down alternately, they standing up when the stroke is to be made, and lying flat when they return to begin a new stroke. Thus this arrangement, by very simple machinery, can effectually use the whole power of the same for the required purpose. The same apparatus may be used for propelling air ships, and the double oscillating motion of the horizontal shaft may be employed on different machinery. I shall now proceed to describe my device, with reference to the accompanying drawing.

A is the stern of a vessel; B is a vertical shaft arranged therein, to which an oscillating motion is imparted either by means of the crank *a*, fig. 2, connecting-rod *b*, and wrist-pin *c*; on the revolving wheel *C*, or by any other suitable device. This shaft *B* is either grooved or hollow, or otherwise so arranged that a vertical reciprocating rod, *d*, may move therein up and down, receiving its motion from a walking-beam, *D*, or from any other suitable device. This rod *d* is either directly or indirectly (that is, by elbow *d'* and rod *e*) connected with a pin, *f*, on a horizontal shaft, *E*, which is held in a sleeve, *g*, which is firmly fixed to the upright shaft *B*. By the reciprocating motion of the rod *d*, an oscillating motion is given to the shaft *E* around its own axis, while the same shaft, being held in the sleeve *g*, also oscillates around the axis of shaft *B*, thus receiving a double oscillating motion. To each end of shaft *E* is secured a paddle, *h*, which paddles are, by means of the double oscillating motion of the shaft *E*, moved so as to drive the vessel either forward or backward, as may be desired. To drive the vessel forward, the paddle will stand upright as it is moved back, (see *h*, fig. 3,) while moving forward it lies flat, so as to cut through the water, (see *h'*, fig. 3;) or, in other words, by the oscillating motion around its own axis, each paddle is placed upright as soon as it is, by the oscillating motion around the axis of shaft *B*, brought as far forward as possible, so as to press with all power against the water during its backward move. The paddle on the opposite end is always in the opposite position, so as not to lessen the full power of the stroke. The driving machinery must, of course, be so arranged that the motions are simultaneous, as described.

What I claim as new, and desire to secure by Letters Patent, is—

The arrangement herein shown and described for propelling vessels, consisting of the paddles *h*, shafts *E* and *B*, rod *d*, pin *f*, and sleeve *g*, substantially as set forth.

SAMUEL B. WAIT.
